INVENTOR
Holmes Marshall,
By Barry Macklin,
HARRY.

UNITED STATES PATENT OFFICE.

HOLMES MARSHALL, OF CLEVELAND HEIGHTS, OHIO.

SAFETY-DEPOSIT-LOCKING DEVICE.

Application filed February 14, 1924. Serial No. 692,671.

This invention relates to improvements in locks and latches and refers more particularly to a combined guard and indicator which is adapted to be used for the purpose 5 of ascertaining whether or not a lock has been surreptitiously opened. Such locks are particularly useful for sealing safety deposit boxes, hand bags and the like.

A device heretofore used for indicating 10 the condition of a lock comprises a card, or data slip, which is so positioned with reference to the lock that it is mutilated whenever the lock is opened. This device required the use of a perforating member 15 together with suitable mechanism for operating it. Usually such mechanism is more or less intricate and uses valuable space within the safety deposit box.

An object of my invention, therefore, is 20 the provision of means for effecting the mutilation of a slip without requiring the use of intricate or comparatively bulky mechanism. In this connection my invention is concerned with a device which may 25 be readily attached to safety deposit boxes, pad locks and the like.

I accomplish the above objects by providing a card or slip holder which is mounted in front of the keyhole and is sealed 30 thereagainst when the lock is closed. To open the lock the key must be forced through the card or slip. To prevent opening of the box and subsequent replacement of the slip by an unauthorized person, the original slip 35 may have the signature of the authorized party and such other indicia as one may see fit to employ.

The means for carrying out the above object will hereinafter be fully set forth in 40 the following description taken in connection with the accompanying drawings, while the essential characteristics will be summarized in the claims.

In the drawings Fig. 1 is a perspective view showing a portion of a safety deposit box having my invention attached thereto; Fig. 2 is a longitudinal vertical section through a portion of the box adjacent the lock; Fig. 3 is a section similar to Fig. 2 50 and showing the cover in partially opened position; Fig. 4 is a view showing a card or data slip which may be used with this invention.

My invention is concerned with the provision of means for effectively holding a 55 slip of paper or other frangible material

across a keyhole opening, wherefore the material must be mutilated before access is provided for the insertion of a key. Accordingly in the various figures I have shown 60 means for retaining such slip or sheet 20, the size and shape of which is dependent upon the type of lock to which the invention is applied.

In Fig. 1 my invention is illustrated in 65 connection with a safety deposit box 21, which is provided with a hinged cover 22, and a front wall 23. The front wall may have an opening to receive a barrel 24 of a lock 25, which is indicated as being disposed behind the front wall of the box. A card or data slip carrier 26 may be hinged at 27 to an attaching plate 28 which is shown as rigidly secured to the front wall 23. This carrier is preferably an L-shaped member, 70 one arm of which has an opening 29 therein sufficient in width to permit the entrance of a key and preferably sufficient in length to display a signature such as is illustrated at 30 in Fig. 4.

To retain the sheet within the carrier I have shown prongs 31 which are disposed on opposite sides of the opening 29 and adapted to pierce the sheet as at 32. As an additional precaution I prefer to employ a 85 sheet the width of which is sufficient to extend substantially the entire width of the carrier, when folded on the line 34. Accordingly, when the carrier is thus moved to the active position as indicated in Fig. 2, 90 then the slip is prevented from being moved laterally with respect to the carrier by cover side flanges 35. In addition the slip is retained by reason of the fact that a hook 36 carried on the underside of the cover extends through an opening 37 in the carrier, 95 then through the slip, and projects into the lock 25. The carrier is positioned by a front flange 38 when the cover is in closed position.

A lock made in accordance with my invention may be very easily adapted for use on safety deposit boxes since the carrier may be readily attached to the front plate of the box. For the purposes of a bank or other institution maintaining safety deposit service, a record of the patrons may be made on a sheet 20, which signature must correspond with that originally given to the bank. The patron may then accompany the custodian 100 to the vault where the boxes are stored, whereupon the custodian may open the compartment. The signature on the slip pre- 105 110

pared by the patron should also correspond to the signature on the slip previously deposited within the carrier. After the box is opened punctured slip is removed and the new one is substituted before the box is closed. The removed slip is then stamped with a date stamp, and filed away as a record that the patron had access to the box on that date.

10. In view of the foregoing description it will be understood that my invention provides a simple compact means which is readily adapted for attachment to boxes equipped with locks, and is especially advantageous 15 for use in banks which maintain a safety deposit box service. Moreover the invention is capable for use in locking articles such as handbags and the like wherein a chain may be fastened around the article and the 20 hasp of the lock passes through a link in the chain. A particular characteristic of the invention is the protection afforded by the mutilation of a record sheet upon opening of the lock.

25. I claim:

1. In combination, a lock, a hinged member coacting with the lock, a card holder hinged to swing in front of the lock and having a lateral extension, said extension having an 30 opening adapted to receive the hinged member, when the lock is closed, and a card disposed within the holder across the keyhole of the lock, said card functioning as a barrier to prevent access to the keyhole until 35 the card is mutilated.

2. In combination with a container, a lock, a hinged member for holding the container closed and arranged to be swung into engagement with the lock, a card carrier 40 hinged in front of the lock, a data card, means associated with the carrier for removably positioning said card so that the keyhole of the lock is concealed when the carrier is swung across the face of the lock, 45 and means engaged by said member for maintaining the carrier in this last mentioned position until the lock is opened, the releasing of said lock being prevented until the card is mutilated by the passing of a key therethrough to gain access to the keyhole.

3. In combination with a container, a lock, a hinged member coacting with the lock to hold the container closed, a carrier disposed 50 in front of the keyhole to the lock and having an opening therein for receiving said member to lock the carrier substantially simultaneously with the closing of the lock, said carrier having a card therein, and said card being disposed in front of the keyhole 55 when the lock is closed, whereby the card must be mutilated before access to the keyhole is provided for purposes of releasing the lock.

4. The combination with a box having a 60 cover, a lock adapted to lock the box closed

and having a key hole, a plate hinged to the box and provided with means adapted to engage a card held across the keyhole, said plate having a portion adapted to be engaged by the cover, whereby, when the box 70 is locked, the card will be locked in place across the keyhole.

5. In combination, a box, a cover therefor, a lock for the cover, a card holder, said holder being disposed in front of the lock, 75 a member on said cover projecting through said holder when the box is closed, and a card within said holder, said card providing a barrier through which a key must be passed before access can be had to the key- 80 hole.

6. In combination, a box having a cover, a lock, a carrier hinged to the box and having a laterally extending portion projecting 85 across the top of the box, said portion being engaged by the top of the cover for preventing movement of the holder with relation to the box, and a card within the holder disposed across the keyhole of the lock, said holder having an opening therein in registration with the keyhole, whereby the card must be mutilated before a key can be passed into the keyhole.

7. In combination, a box having a hinged cover therefor, a lock within the box, a member on the cover coacting with the lock, a carrier positioned on the box and having a laterally extending portion projecting across the top thereof, said portion having an opening therein for receiving said member when the cover is closed, and a card within said holder, said card being disposed in front of the keyhole whereby the card must be mutilated before access to the key- 100 hole is provided.

8. In combination, a box having front and side walls and a hinged cover, a lock adjacent the front wall, a card holder hinged to the front wall below the lock, a card within said holder, said holder being adapted to swing about the hinged connection so as to bring the card across the keyhole for the lock, said cover having a flange extending downwardly in front of the holder, whereby the holder is maintained in proper position to prevent surreptitious removal of the card, and whereby the card forms a barrier which must be mutilated before access to the key- 110 hole is attained.

9. In combination, a box, a hinged cover therefor, a lock between the box and cover, a card holder comprising an L-shaped member hinged to the box in such a manner that one arm thereof is adapted to extend across the keyhole for the lock, and the other arm thereof is adapted to extend across the wall of the box and to be engaged by the underside of the cover, a card folded to conform to the shape of the holder, and means associated with the holder for preventing a lateral 120

movement of the card with reference thereto, said card being disposed across the keyhole when the holder is moved into an active position, whereby the card provides a barrier 5 which must be mutilated before the key can enter said keyhole.

10. In combination, a box, a hinged cover therefor, a lock between the box and cover, a card holder comprising an L-shaped member hinged to the box in such manner that one arm thereof is adapted to project across the keyhole for the lock and the other arm is adapted to extend across the top of the box, said cover preventing angular movement of 15 the holder with relation to the box when the box is locked.

11. In combination, a box, having a cover therefor, a lock, a member on the under- 20 side of the cover adapted to enter the lock, a card holder having one end thereof hinged in front of the lock and having the free end thereof adapted to extend across the top of the box and to be engaged by the under side of the cover for preventing angular move- 25 ment thereof with reference to the box when the cover is closed, said holder having an opening therein, a card within said holder, and a member carried by the cover and projecting through the opening, and also 30 through said card whereby the card may be held within the holder against surreptitious removal when the box is closed.

12. In combination, a box, a cover there-

for, a lock, a card holder hinged to the box and adapted to extend across the top thereof, 35 said holder having an opening adjacent the top portion, a member carried by the cover and adapted to extend through said opening and to enter the box for locking the holder against movement with reference to the box 40 when the box is closed, a card within said holder, said card being pierced by said member for retaining it in position with reference to the holder, and said card being disposed in front of the keyhole for concealing 45 it when the holder is moved into locking position, said holder having an additional opening in registration with the keyhole to permit the entrance of the key, and said card preventing entrance of the key into the key- 50 hole until the card is mutilated.

13. In combination with a container, a lock therefor, means coacting with the lock to hold the container closed, a card and a carrier therefor movably carried by the container adapted to be positioned across the lock to conceal the key hole thereof by a portion of the card, and means on the carrier engaged by said first named means when the container is closed to prevent movement of 55 the carrier, said preventing means cooperat- 60 ing with the container to completely conceal the lock.

In testimony whereof, I hereunto affix my signature.

HOLMES MARSHALL.
